UNITED STATES PATENT OFFICE.

RODERICK W. DAVIES, OF CHICAGO HEIGHTS, ILLINOIS.

DUMPING-CAR.

1,079,977.

Specification of Letters Patent.

Patented Dec. 2, 1913.

Application filed March 1, 1912. Serial No. 680,853.

To all whom it may concern:

Be it known that I, RODERICK W. DAVIES, a citizen of the United States, residing at Chicago Heights, in the county of Cook and State of Illinois, have invented certain new and useful Improvements in Dumping-Cars, of which the following is a specification.

My invention relates to dumping cars and is particularly designed to provide a structure of dumping car comprising a plurality of doors hinged at their inner ends and desirably along parallel lines at the approximate center of the car.

In the production of a dumping car embodying the advantageous features of my invention, I aim to eliminate excessive stress upon the parts and to decrease the requisite power for opening and closing the doors of the dumping car by providing comparatively flexible bars connected to the outer corners of the doors and controlled by sprockets upon shafts driven by hand operated worm gearing.

Actual practice has demonstrated that excessive stress and consequent tendencies to breakage, are largely obviated by the provision of my type of controlling mechanism for the doors of a dumping car.

The preferred embodiment of my invention is shown in the accompanying drawings, in which similar characters of reference designate corresponding parts, and in which—

Figure 1 is a top plan view of a portion 25 of a dumping car, Fig. 2 is an end elevation thereof, Fig. 3 is a vertical sectional view taken on line 3—3 of Fig. 1 and looking in the direction of the arrows, Fig. 4 is a detail plan view of a portion of the outer 40 bars for the doors of my dumping car, and, Fig. 5 is an edge elevation of the structure shown in Fig. 4.

In the drawings, the dumping car is shown at 1 as comprising a plurality of doors 2 varying in number according to circumstances, and pivoted at their inner edges to the center sill 3 by hinge members 4. These doors are desirably provided with castings 5 to which are pivotally connected 50 ladder bars comprising sections 6, 7 and 8 of a size to extend and fit within pockets 9 formed in the sides of the car. These pockets 9 also serve to reinforce and brace the side of the car against bulging.

Extending longitudinally the length of the car and just without the lower corner

thereof are shafts 10, desirably two for each side of the car. These shafts carry sprockets 11 suitably positioned to coact with and control the movement of the pivotally connected ladder sections 6, 7 and 8 pivotally connected to each other. In addition, the ends of the shaft 10 are also provided with worm wheels 12 meshing with worms 13 upon manually operable shafts 14 provided with hand wheels 15. Each ladder section is preferably made of two side members 16 and 17 rigidly spaced apart by a plurality of rung members 18. These rung members are adapted to coact with the sprocket teeth and thereby control the movement of the swinging doors.

It will be observed that I have provided a structure whereby all of the doors along a half of one side of a car, may be 75 manually controlled by the rotation of a hand wheel. It will be observed that this is effected through the medium of elements connected to the outer extremities of the doors, which elements are of such form as 80 to insure sufficient rigidity and guard against breakage from strain. In addition to this, the utilization of a worm wheel and worm for controlling the sprocket shafts, serves to produce an automatic lock for the 85 doors at any position of adjustment.

What I claim, is:—

1. A dumping car comprising a body portion, a plurality of doors hinged at their inner edges, a plurality of ladder sections 90 pivotally connected to each other and to the outer edges of said doors, and hand controlled sprocket wheels for operating said ladder sections for altering the position of said doors.

2. A dumping car comprising a body portion, a plurality of doors hinged at their inner edges, ladder sections pivotally connected to each other and connected to the outer edges of said doors, sprockets for operating said ladder sections, and a worm gear control for said sprockets.

3. A dumping car comprising a body portion, a plurality of doors hinged at their inner edges, flexible sections connected to 105 the outer edges of said doors and adapted to be telescoped vertically within a pocket formation on the side of the car, driving sprockets for said flexible sections for altering the position of said doors, and driving 110 means for rotating said sprockets.

4. A dumping car comprising a body por-

tion, a plurality of doors hinged at their inner edges, ladder sections pivotally connected to each other and connected to the outer edges of said doors and comprising a plurality of side members arranged in pairs, each pair being pivotally connected to its succeeding pair, spaced rungs interposed between the pivotal connections of each pair of members, sprockets for operating said

ladder sections, and a worm and worm wheel driving means for said sprockets.

In testimony whereof I affix my signature in presence of two witnesses.

RODERICK W. DAVIES.
